[57] CLAIM

[21] Appl. No.: 29/087,854

The ornamental design for a support arm for a sliding compound miter saw, as shown and described.

[22] Filed: May 11, 1998

DESCRIPTION

Related U.S. Application Data

FIG. 1 is a perspective view of the design for a support arm for a sliding compound miter saw according to the present invention;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line showing of the sliding compound miter saw is for illustrative purposes only and forms no part of the claimed design.

The ornamental design for a support arm for a sliding compound miter saw, as shown and described.
